(57) **CLAIM**

The ornamental design for an electric actuator as shown and described.

DESCRIPTION

FIG. 1 is a front, top and right perspective view of an electric actuator comprising a new, original and ornamental design; FIG. 2 is a front view thereof; FIG. 3 is a rear view thereof; FIG. 4 is a left view thereof; FIG. 5 is a right view thereof; FIG. 6 is a top view thereof; and, FIG. 7 is a bottom view thereof.

The broken lines in the drawings illustrate portions of the electric actuator that form no part of the claimed design.
